US0D1042109S

(12) **United States Design Patent** (10) Patent No.: **US D1,042,109 S**
(45) Date of Patent: ** Sep. 17, 2024

(54) **PACKAGE**

- (71) Applicant: **GlaxoSmithKline LLC**, Wilmington, DE (US)
- (72) Inventors: **Leonard Joseph Dichiara**, Chatham, NJ (US); **David Michael Lutness**, Hillsborough, NJ (US); **Jeffrey Scott Brunner**, Parsippany, NJ (US); **Peter Kay**, Ware (GB); **James Andrew Holt**, Worthing (GB)
- (73) Assignee: **GLAXOSMITHKLINE LLC**, Philadelphia, PA (US)

(**) Term: **15 Years**

(21) Appl. No.: **29/780,251**

(22) Filed: **Apr. 23, 2021**

Related U.S. Application Data

- (62) Division of application No. 29/585,377, filed on Nov. 23, 2016, now Pat. No. Des. 920,093, which is a (Continued)

(57) **CLAIM**

We claim the ornamental design for a package, as shown and described.

DESCRIPTION

FIG. 1 is a front perspective view of a package; FIG. 2 is a rear perspective view of a package; FIG. 3 is a front view of a package; FIG. 4 is a rear view of a package; FIG. 5 is a top view of a package; FIG. 6 is a bottom view of a package; FIG. 7 is a right side view of a package; and, FIG. 8 is a left side view of a package. The broken lines shown in the drawings depict portions of the package that form no part of the claimed design.

1 Claim, 6 Drawing Sheets

Related U.S. Application Data

division of application No. 29/472,343, filed on Nov. 12, 2013, now Pat. No. Des. 775,945.
